UNITED STATES PATENT OFFICE.

GEORGE H. FOULKS, OF SAN FRANCISCO, CALIFORNIA.

ELEVATOR SAFETY AND ANNOUNCING DEVICE.

No. 895,848.

Specification of Letters Patent.

Patented Aug. 11, 1908.

Application filed October 10, 1907. Serial No. 396,790.

To all whom it may concern:

Be it known that I, GEORGE H. FOULKS, citizen of United States, residing in the city and county of San Francisco and State of California, have invented new and useful Improvements in Elevator Safety and Announcing Devices, of which the following is a specification.

My invention relates to an automatic safety and announcing attachment for elevator cages.

It consists in the combination of parts, and in details of construction, which will be more fully explained by reference to the accompanying drawings, in which—

Figure 1 is a sectional elevation of the cage and its attachments. Fig. 2 is a similar sectional elevation taken transversely to the door opening of the elevator shaft. Fig. 3 is a bottom view showing a portion of the mechanism. Fig. 4 is an enlarged view of the latching mechanism disengaged. Fig. 5 is a detached view of the safety stop. Fig. 6 is a section through the star-wheel. Fig. 7 is an end view of same. Figs. 8 and 9 show the ratchet mechanism, and Fig. 10 is a rear view of the latch.

It is the object of my invention to provide a mechanism attached to elevator cages, which will automatically stop a car or cage which prematurely leaves a floor or station while receiving or discharging passengers. Other safety devices are used to protect people before or after entering the car, but my device will operate automatically when the car starts while the door is open, or when the controlling mechanism becomes out of order while receiving or discharging passengers, and its use will not delay traffic by requiring absolute precision, necessary to the operation of other safety locking devices.

As shown in the drawings, A is an elevator cage moving in the usual shaft or well B, and C represents a door, opening through the wall of the shaft, and through which access may be had to, and exit from, the cage, when the latter is on a level with the floor. The cage is provided with safety clutches or latches 2, as plainly shown in Fig. 3, and these latches are forced outward to engage the notched receivers (Fig. 5) attached to the guide rails or equivalent stops between which the cage travels, so that if the cage suddenly leaves the station while the doors are either fully or partially opened, and passengers moving either in or out, the mechanism will be ac-

tuated so as to stop and lock the cage before it has proceeded far enough to cause any injury or damage. This mechanism is controlled as follows: The slideable bars 3 are movable in guides, as at 4, the bearings consisting of metal covered hard rubber cushions, and are actuated by means of a fulcrumed lever 5, and universally jointed rods 6, and rod 6^a, connecting this lever with a double crank-arm 7, suitably fulcrumed with relation to the cage, and having the end opposite to its connection with the lever 5 connected with a spring and weight-actuated arm or rod 8. This rod is normally held in such position that the safety catches 2 are withdrawn from contact, and the cage may move freely; but where the necessity occurs, the rod is released and the parts allowed to act automatically.

I have here shown two equivalent means for actuating the slideable rod or bar, one being a spring 9, and the other a weight 10 carried by a bent lever 11, which is fulcrumed at 12, and has an upturned end engaging with a slot or channel in the rod 8. When spring 9 is compressed by lever 18 (which normally lies flat on car floor) and the weighted lever 11 is simultaneously raised, the parts are held in position by means of a pivoted latch 13, one end of which acts to hold the rod 8 backwardly against the spring, and the other end is adapted to rest upon the intermediate points of a latch-wheel 14, which wheel or pinion is carried upon a vertical shaft or sleeve 15; and the parts remain thus supported until the necessity arises for disengaging them. This disengagement is effected by turning the vertical shaft sufficiently to allow the holding end of the latch 13 to fall between two of the arms, and, as it drops, it releases the spring 9 and the weighted arm 11, and their combined movement forces the rod or bar 8 to actuate the latches or clutches, as previously described. When the parts are to be restored to their position, the conductor effects the same by means of lever 18 acting against rod 8, and a ring or lifter 16 connected by a flexible cord or chain 17 with the lever 11. By this means rod or bar 8 is pressed back and the weighted arm 11 is lifted and latch 13 restored and again engaged with one of the arms of the latch-wheel 14, in which position it will remain until again released.

The sleeve 15 is loosely turnable around a rod or shaft 20. The sleeve has a beveled

pinion 21 fast upon its lower end, and the shaft 20 projects far enough below this pinion to carry an independently operated beveled pinion 22. This sleeve and shaft extend up 5 through the interior of the cage at a convenient point, and the sleeve carries bevel gears at the upper end, which engage with mechanism actuated by other mechanism upon the door C; and through these connections 10 the locking mechanism is disengaged, as before described, if the door is partly open when the cage leaves the floor. The shaft 20, carrying the beveled pinion 22, passes through the cage and connects with the shaft 15 30, by a beveled pinion which manipulates the sprockets 27 and 28 and chain 26, revolving the rollers 32 which display floor-announcing and advertising signs. The door mechanism consists of arms 24 projecting 20 from the door C and foldable in one direction. These arms are in engagement with the co-acting parts carried by the cage as follows: When the door is closed, the first of a series of radially armed disks or star-wheels 25 will 25 be engaged and will actuate an indicator 32 to show the different floors. If the door is left slightly open, the arm or lug 24 will engage the next star-wheel 25^a and will sound a warning bell 35. If still further open, the 30 next star-wheel 25^b will be engaged, and will act to sound an alarm gong 36, while, if the door is so far opened as to leave a passage through which a person might try to pass, the last star-wheel 15^a will be engaged, and this 35 will actuate the stop or clutch mechanism. Four of these radially armed or star-wheel disks are here shown. They are all mounted upon a shaft 30, and the first one 25 is keyed to the shaft and will always be revolved 40 when the door is closed, and the cage is moved up or down, so as to indicate the number of the floor, or other desired information. The next two star-wheels are loosely turnable upon the shaft, and do not 45 act when the door is properly closed. If by accident a door should be left slightly open or not fastened, when the car moves up or down, the arm 24 would be moved far enough to engage the wheel 25^a and this in turning 50 would act through a press button 37 or equivalent device, to sound a warning bell 35. If the door should be still further open, but still short of actual danger, the arms 24 will engage with and turn the wheel 25^b, which acting 55 through connection 38 will sound the larger alarm gong 36, as a danger signal to the operator.

If the door is so far open that a passenger might attempt to enter or go out, or get 60 caught in any way when the car starts, through the fault of the conductor, or by reason of defective mechanism, the arms 24 will engage the wheel 15^a which is mounted upon a sleeve 39 turnable upon the shaft 30.

65 This sleeve carries a pinion 40, shown in Fig.

1, and through a short shaft 41 with pinions upon each end, the pinions 21 and 21^a upon the bottom and top of the sleeve 15 will be turned to release the brake or stop mechanism, and stop the cage in time to prevent injury to the person who might attempt to pass after the cage had been started. 70

The star wheels may be associated with a suitable spring plate having a notch. For instance, in Fig. 9, I show the notched spring 75 attached to the cage A so as to contact with the arms of the star-wheel 25^a, and permit this wheel to revolve one eighth of a revolution at each engagement with the arm 24.

The star-disks or wheels above described 80 are provided with ratchet pawls or equivalent clutches or devices, which allow each preceding disk to turn independently of the others, but when the door has been opened far enough to engage with any wheel beyond 85 the first, that wheel will, through its ratchet, engage and turn the preceding one so that the first wheel 25 will always be turned, and the connected parts will partake of its motion. 90

By means of the sprockets 27—28 and the chain 26, motion is communicated to revolve one of the indicating rollers 32, and the shaft of this roller may, if desired, carry pinions 32^a, through which and coacting pinions on 95 other roller shafts, a series of rollers 32 extending around the interior of the cage, may be revolved.

A hand-wheel 31 is fixed to the sleeve 15 within convenient reach of the conductor 100 within the cage, so that sleeve 15 operating latch-wheel 14, may be turned by hand, when desired to operate the safety clutch or restore it after it has been put in operation.

Both of the engaging arms 24 are spring-105 pressed to project into the path of travel of the sprocket wheels, but they are so fulcrumed that one of them simply folds without acting when the cage is going up, and becomes rigid when the cage is coming down, 110 the other acting in the opposite way; that is, it acts when the cage is going up, and is inactive when the cage is coming down. These are always operated in conjunction with the first of the drums 25, which will be moved in 115 unison with the movements of the cage. But if the door is, as before stated, in an improper position, these arms 24 will be so shifted as to engage another of the drums, as 25^a or 25^b or 15^a, and these will also actuate the alarms 120 or safety operating device.

The safety clutch mechanism operates automatically only when a car has reached a point from ten to twenty inches above or below a floor, and before a considerable momentum has been attained, thereby avoiding a severe jar to the passengers, or requiring a heavy construction of the different parts; and the notched plates designed to receive the clutches or latches need only be attached 130

to the guide rails for a distance of about three feet above and below each floor landing.

Having thus described my invention, what I claim and desire to secure by Letters Patent is—

5 1. In an elevator apparatus of the character described, the combination of a cage, a brake or stop mechanism carried thereby, doors in the elevator well, and devices carried by the doors, said devices acting automatically when they are brought into the range of action of the brake or stop mechanism carried upon the cage when the door is not fully closed, to apply said brake and stop the cage.

10 2. In an elevator apparatus of the character described, a cage, a brake or stop mechanism carried upon the cage, doors in the elevator well, lugs or arms projecting from the doors, revolvable star-wheels upon the cage, engageable by the lugs, said devices acting automatically when the door is not fully closed to apply said brake and stop the cage.

15 3. In an elevator apparatus of the character described, a cage, a brake or stop mechanism carried upon the cage, doors in the elevator well, lugs or arms projecting from the doors, revolvable star-wheels upon the cage, engageable by the lugs, said devices acting automatically, when the car moves up or down and the door is not fully closed, and a device within the car operated by the conductor, for the purpose of applying said brake to stop the cage.

20 4. In an elevator apparatus of the character described, the combination with notched receivers or guide rails, of a cage, a brake or stop mechanism carried upon the cage having a bar with elastic bearings to relieve the jar when said brake or stop mechanism is brought in contact with the notched receivers or guide rails, doors in the elevator well, and devices carried by the doors, said devices acting when the door is not fully closed to apply said brake or stop mechanism, and stop the cage.

25 5. In an elevator apparatus of the character described, a cage, a stop or brake mechanism carried upon the cage, a latching device whereby said stop mechanism is normally held out of engagement, disengaging devices upon the cage contiguous to the wall of the elevator shaft, a door in said shaft, and lugs projecting from the door adapted to disengage the latching device and apply the stop mechanism when the door is not fully closed.

30 6. In an elevator cage mechanism, a cage, spring and weighted-actuated stops, a means for normally holding said stops out of engagement, a latch-wheel carried under the cage having connection with the stop-actuating mechanism, doors slideable in the wall of the elevator well, through which doors access is had to or from the cage, lugs carried by said doors star-wheels attached to said cage and alarms actuated by said lugs pro-

jecting from said doors, normally in line with the star-wheels and operating the indicator only when the door is fully closed, said lugs being brought into line to engage the star-wheels controlling the alarms, and then to engage the star-wheel when the door is left partially open.

7. In an elevator apparatus of the character described a cage, a stop or brake mechanism carried by the cage, a slideable spring and weight-actuated bar connected with the stop mechanism, a latch-wheel, a latch engageable with said latch-wheel to normally hold the stop mechanism out of action, a revolvable shaft upon which the latch-wheel is carried, 70 gears by which said shaft is turnable to disengage the latching mechanism from the latch-wheel, a star-wheel and intermediate mechanism by which the shaft may be turned herefrom, slideable doors at the entrances of the elevator shaft, and lugs carried upon said doors, out of line of engagement with the star-wheel controlling the stop mechanism when the door is closed, said lugs being brought into line with such star-wheel, 80 when the door has been left partially open, whereby the stop mechanism will be actuated.

8. In an elevator apparatus of the character described a cage, a shaft vertically journaled within the cage and a sleeve independently turnable upon said shaft, a latch-wheel carried by the sleeve, a pressure actuated stop or brake mechanism, a latch engaging a point in the latch-wheel whereby the stop mechanism is normally held out of engagement, a star-wheel journaled upon the cage, intermediate mechanism whereby the sleeve and controlling latch-wheel may be turned to release the latch and brake mechanism, entrance doors in the wall of the elevator well, and spring-pressed foldable lugs upon the top and bottom of said doors, normally out of line with the journaled star-wheel, one of said lugs being capable of engaging the star-wheel when the cage is moving upward, and the other when the cage is moving downward.

9. In an elevator mechanism of the character described, a vertically movable cage, 115 horizontally slideable entrance doors in the wall of the elevator well, lugs carried by said doors projecting into the path of movement of the cage, star-wheels journaled horizontally upon the cage, one of said wheels being engaged and turned by the lugs as the cage passes, an announcing cylinder with intermediate connections whereby it is turned in unison with the movement of the star-wheel, other star-wheels mounted in line with the first-named wheel so as to be engaged by the door lugs when the door has been left partially closed, a brake or stop mechanism carried upon the cage, a shaft, a latching device whereby the stop mechanism is held in dis- 120 130

engaged position, and a holding means carried by the shaft and normally engaged by the latch, said means being disengaged to release the brake mechanism when the door is sufficiently open to engage the last of said star-wheels.

10. The combination with an elevator cage, its well and entrance doors, of lugs or arms projecting from the doors, a series of independently revolvable star-wheels upon the cage, engageable by the lugs, and indicating and alarm devices with connections by which said devices may be separately actuated.

11. The combination with an elevator cage, its well and entrance doors, of lugs or arms projecting from the doors, a series of independently revolvable star-wheels upon the cage, engageable by the lugs, and indicating, alarm, and stop devices with connections by which said devices may be separately actuated.

12. The combination with an elevator cage, its well and entrance doors, of lugs or arms projecting from the doors, a series of independently revolvable star-wheels upon the cage, engageable by the lugs, and indicating, alarm and stop devices with connections by which said devices may be separately actuated, in combination with a shaft vertically journaled within the cage with a handle within reach of the conductor, and connected with the stop device.

13. The combination with an elevator cage, its well and entrance doors, of lugs or arms projecting from the doors, a series of independently revolvable star-wheels turnably mounted upon the cage, and successively en-

gagable by the lugs when a door is increasingly opened, an indicator actuated by the first wheel, an alarm by the following wheels, and a brake or stop mechanism by the last wheel.

14. The combination with an elevator cage; its well and entrance doors; of lugs or arms projecting from the doors; independently turnable star-wheels carried upon the cage and successively engageable by the lugs with different openings of a door; indicating, alarm and stop mechanisms, connections by which each is actuated from its connected wheel, and pawl and ratchet devices whereby motion of succeeding disks is communicated to preceding ones.

15. The combination with an elevator cage, its well and entrance doors, of lugs or arms projecting from the doors and foldable in opposite directions, sets of turnable star-wheels carried upon the upper and lower part of the cage, mechanism by which successive members of both sets are connected with successive indicating, alarm, and brake or stop devices, the members of one set being actuated by the rigid door lug and passed by the foldable lug when the cage is moving in one direction, and the other set being actuated by the other lug when the cage moves in an opposite direction.

In testimony whereof I have hereunto set my hand in presence of two subscribing witnesses.

GEORGE H. FOULKS.
